UNITED STATES PATENT OFFICE.

EARL V. SALA, OF TOLEDO, OHIO, ASSIGNOR TO THE E. V. SALA PATENTS COMPANY, OF TOLEDO, OHIO, A CORPORATION OF OHIO.

ENGINE.

1,266,165.

Specification of Letters Patent.

Patented May 14, 1918.

Application filed April 18, 1915. Serial No. 20,770.

To all whom it may concern:

Be it known that I, EARL V. SALA, a citizen of the United States, and a resident of Toledo, in the county of Lucas and State of Ohio, have invented a certain new and useful Engine; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

15 My invention relates to internal combustion engines and it has for its object to provide an engine which may be made at a low cost of production and yet one which is exceedingly efficient and has a very few 20 number of movable parts. It particularly has for its object to provide a silent running engine wherein the cylinders may be charged with the explosive mixture and wherein the products of the combustion may 25 be completely discharged at the minimum amount of loss of energy in the operation of the engine.

By my invention a means is provided for 30 rapidly opening the passageways for the fuel and burnt gases to their fullest extent. Also, a means is provided whereby the passageways leading to and from the engine during the periods of the exhaust and the intake will be completely opened at the 35 times that the engine in its cycles of operation is ready to receive or eject the materials contained in the cylinders. Also, in constructions containing my invention, the explosive mixture is heated by the heat 40 of the exhaust products and, consequently, the passageways through which the ejected products pass are correspondingly cooled. Also by my invention means is provided for sealing the cylinder during the compression 45 and power strokes from any possible leakage. Also, by my invention springs are done away with in the operation of the gates or valves or closing devices for closing the 50 ports and passageways leading to and from the cylinders of the engine and consequently there is but little loss of energy in the operation of the valves against the springs in the performance of the engine. Also, by

my invention the openings are positively performed by mechanical means and are not 55 dependent upon the yielding operation of elastic means. Also, means may be easily provided whereby auxiliary ports may be formed in parts of the engine whereby additional area may be given to the intake 60 passageways or the exhaust passageways, or both.

Also, my invention provides an engine wherein the parts may be readily assembled or removed, repaired and replaced and 65 wherein the movable parts are subject to the least possible wear and tear. Also, by my invention the pressure and the work required to operate the gates of the passageways is reduced to a minimum. Also, by 70 my invention the friction between the parts is greatly reduced.

The invention may be contained in many forms of engines usable for different purposes, all of which come within the purview 75 of my claims hereinafter appended. To show the practicability of my invention, I have selected one form of engine as an example and shall describe it hereinafter. The construction selected is illustrated in the 80 accompanying drawings.

In the figures, Figure 1 is a vertical, sectional view taken on the line 1—1, shown in Fig. 2. Fig. 2 is a top and transverse sectional view of the engine taken on the line 85 2—2, indicated in Fig. 1. Fig. 3 is a vertical sectional view taken on the line 3—3, indicated in Fig. 2. Fig. 4 is a top view of the upper part of the engine. Fig. 5 illustrates a side view of the upper part of 90 the cylinder casing showing the manifolds connected with the engine. Figs. 6, 7, 8 and 9, illustrate in a diagrammatical and conventional way a section through the engine showing the relative positions of the 95 pistons to the ports and passageways, in the cyclic operations of the engine.

1, 2, 3 and 4 indicate engine elements, that is, the parts of the engine which coöperate to drive the crank shaft. They form what 100 is known in the art, as a four-cylinder four-cycle engine.

The engine is provided with a casing 10 which is common to all of the elements for inclosing the crank shaft and piston rods. 105 It is provided with an upper portion 11

which is bolted to the cylinder casing 12 and the lower portion 13 which is bolted to the portion 11. The lower casing 13 may be provided with a suitable drain plug 14.

- 5 The lower casing 10 is provided with a crank shaft 15 which extends between the parts 11 and 13 and is supported in suitable bearings 16. The piston rods 17 are connected to the crank shaft 15 and to the 10 pistons 21, 22, 23 and 24. The pistons are provided with the rings 19 which seal the interior of the cylinder from leakage during times of the explosion and the compression. The cylinder casing 12 is provided 15 with a suitable jacket having the chamber 18 for containing water or other cooling medium for reducing the temperature of the engine. The pistons move in sleeves or cylinders 31, 32, 33 and 34 which are located 20 within the casing 12 of the engine. The cylinders are longitudinally movable in the engine casing 12. They are positively operated by the crank shaft of the engine or by some other means which will synchronously 25 operate the cylinders with respect to the movements of the piston. The cylinders may be driven by a sprocket gear 25 located on the crank shaft 15. The crank shaft 15 is connected to a crank shaft 26 by means of a sprocket chain 27 and a sprocket gear 28. The crank shaft 26 is connected to whip rods 35 which are connected to pairs of ears or bifurcated arms 36 extending from the cylinders 31, 32, 33 and 34. The 30 crank shaft 26 is supported in bearings 29 at the ends of the casing 10. The cylinders are provided with ports and the engine casing is provided with passageways for controlling the flow of the fuel and burnt gases 35 of the engine. The connections between the pistons of the engine and the cylinders are such that they move in a two-to-one relation, that is, the pistons make two strokes in a given direction, while the cylinders 40 make a short single stroke. The strokes of the cylinders are such that they quickly open the passageways of the engine to their widest extent and quickly close them while the pistons are performing their operations 45 in the cycles of the engine elements.
- 50 The cylinders 31, 32, 33 and 34 extend to near the top of the casing. The casing is provided with caps 37 which are bolted at the top of the engine. They extend down 55 into the casing 12 forming heads 38 which extend well within the cylinders. The heads 38 are so located as to extend below the upper edges of the cylinders when they are at their lowermost positions in the operations 60 of the crank shaft 26. An annular pocket 39 is thus formed between the heads 38 and the casing 12 in which the cylinders 31 may slide. The heads 38 are provided with jacket chambers 45 which communicate with 65 the jacket chambers 18 in the casing for

keeping the heads 38 cool. The heads 38 are provided with passageways 41, 42, 43 and 44 for the burnt gases and also passageways 51, 52, 53 and 54 which communicate with the fuel supply of the engine. The 70 passageways of one kind are separated from the passageways of the other kind by webs 46 which are formed in the heads 38. The lower ends of the heads 38 terminate in explosion or combustion spaces 47. The 75 lower ends of the heads 38 are provided with packing rings 48 which seal the engine from leakage. The water chambers 45 extend through the passageways located at the sides of the head and the side of the 80 webs 46 and into the lower end of the head. The ignition plugs 56 are inserted in the heads and extend into the explosion space 47 whereby the explosive charges are ignited at the beginning of the power stroke 85 in the manner well known in the art. The plugs 56 extend into pockets 57 and through the lower end of the head 38, their terminals extending into the explosion space formed in the lower end of the head 38. 90

The passageways 41, 42, 43 and 44 and the passageways 51 to 54 which communicate respectively, with the exhaust and intake manifolds of the engine, are controlled by the movable cylinders 31, 32, 33 and 34, 95 respectively. The openings 61, 62, 63 and 64, formed in the cylinders, are adapted to register, either with the exhaust passageways 41 to 44 or with the intake passageways 51 to 54, respectively. The openings 100 61 to 64 in the cylinders permit the gases to pass to and from another of the cylinders, that is, to and from the other cylinder of the pair in which each cylinder is coupled or associated. The arrangement may be 105 such that the openings or ports 61 to 64 will register with the passageways 41 to 44 on one side of the webs 46 when the sleeves have completed one movement and to register with the passageways 51 to 54 on the 110 opposite sides of the webs 46 when the cylinders have completed their opposite movement. In the construction shown the cylinders in moving 180° as measured in the 115 circles of the crank pins to which they are connected, move so as to completely open either set of passageways to the engine element controlled by them.

The cylinders or sleeves are also provided with openings which permit the gases to 120 pass into and out of them to drive the engine pistons and to exhaust the cylinders. The ports or openings 71, 72, 73 and 74 permit the gases to enter and exhaust from the cylinders from and through the passageways formed in the heads of the associated engine elements. By this means the passageways leading to each engine element from the source of fuel supply and the passageways which lead to the exhaust of the en- 125 130

gine, from each engine element are controlled by the movements of two cylinders, that is, one set of openings in the cylinders control the direct communication between the engine elements and the manifolds while the other set of openings in the cylinders control the communication between the passageways which are subject to the control of the first set of openings. The second set of openings control the passageways which lead from the engine element of the pair in which it is associated, which controls the direct communication leading to and from the exhaust and intake of the engine.

15 The passageways 81, 82, 83 and 84 interconnect between the engines in pairs. The passageway 81 leads from the exhaust and intake passageways 42 and 52 of the engine element 2 to the engine element 1, while the passageway 82 leads to and from the engine element 1 having passageways 41 and 51. Also, the passageways 83 and 84 interconnect the engine elements 3 and 4 in the same manner.

20 The passageways in the engine which conduct the explosive mixtures and the products of combustion to and from the explosion spaces of the engine may be greatly varied and their arrangement may be greatly altered to suit various conditions, both as to manufacture and as to utility of the engine. Also, the spaces for conducting the cooling liquids may be greatly varied. What I have shown is an illustrative construction that contains my invention which, however, may be greatly modified by those skilled in the art.

The openings 71 of the sleeve 31 controls the connection 81 leading from the passageways 42 and 52, while the passageways 42 and 52 are controlled by the opening 62. The intake of the charging gas and the exhaust of the products of combustion of the engine element 1 is thus dependent upon, not only, the movements of the cylinder 31, but also, the movements of the cylinder 32. The openings 71 to 74 are so located in the sleeves 31 to 34, respectively, as to be 200° in advance of the opening of the intake passageways of the engine elements of which they form a part, that is, the opening 71 is such that it begins to open the passageway 81 at 200° in advance of the time in which the opening 61 opens the intake passageway 51. Also, the opening 71 is of such size and so located in the cylinder 31 that the passageway 81 is closed 20° behind the closing of the passageway 51. The opening ports of the exhaust passageways being 180° from the opening ports of the intake passageways a corresponding relation exists between the opening and closing of the ports to the interior of the cylinders above the pistons. The openings 71 to 74 are located 110° as measured in the circle described by the crank pins of the shaft 26 in advance of the opening of the intake of the engine element of the pairs in which they are associated, that is, the opening 71 begins to open the passageway 81, 110° in advance of the opening of the intake passageway 52 of the engine cylinder 32 or 220° as measured in the circular movements of the crank pin 91 of the piston 21. The openings 71 to 74, however, is 70° after the openings of the exhaust passageway, of the cylinders of the other of the engine elements in the associated pairs, take place, that is, the opening 71 begins to open the passageway 81, 70° after the opening 62 of the cylinder 32 begins to open the exhaust chamber 42, as measured on the circle of the crank pin 102, or 140° as measured by the circular movements of the crank pin 91 to which the piston 21 is connected.

25 The engine elements are connected to the crank shaft at points 90° ahead of each other. The pistons of the engine elements are connected to the crank shafts so as to perform in a certain sequence the cyclic operations of each engine element. In the form shown the engine element 3 follows in sequence the engine element 1 and then the engine element 4 follows in the performance of the same operation of the cycle and then the engine element 2 follows the performance of the engine element 4, so that the engine elements in the order of 1, 3, 4 and 2, perform the four cycles.

30 As shown in Fig. 7, the driving stroke of the piston 21 moves the crank pin 91 from the radial line A to the radial line B. Mean- time, the connection 81 is open by the sleeve 31 which, as indicated by the circular movements of the crank pin 101, passes from the radial line A to the radial line B and when it reaches B the connection 81 is closed. The cylinder 32 has also been moving from a point measured on the crank pin from the radial line A to the radial line B, during which time the intake passageway is open to the connecting passageway 81. So that, while, the crank pin of the engine 21 passes from the radial line A to the radial line B, the intake passageway leading through the connection 81 and the openings 62 and 71 have been opened and, although, during that movement, the piston 31 performs a part of its return, yet the low pressure created within the cylinder 31 by the down stroke of the piston 21 still draws the explosive mixture through the passageways 52 and 81 which convey the explosive mixture from the manifold to the cylinder 31 until the communication is cut off by the sleeve 81 which occurs when the crank pin 91 of the piston 21 moves across the radial line B. It thus has an intake, in this construction, while the crank pins 91 to 94, are moving 220°.

35 As the crank pin of the piston 21 moves

from the radial line A to the radial line B, the port 61 is open and closes when the crank pin reaches the radial line B, although the opening 52, which communicates with the manifold leading from the carburetor, is opened until the crank pin reaches the radial line A, C. During the time of the movement of the crank pin from the radial line B to the radial line A, C, the piston 21 is compressing. Shortly after the movement of the crank pin through the radial line A, C, the explosion takes place and drives the piston until the crank pin passes through the radial line D. When it passes through the radial line D the port 71 opens the connection 81. The exhaust port 42 however, has by this time been opened and was opened when the crank pin 91 passed the radial line A, C, namely, when the crank pin of the sleeve 31 is at C. While the crank pin 91 connected to the piston 21 passes across the radial line D to the radial line A the port 71 is open and also the exhaust port 42 is open, whereby the products of combustion pass out through the ports 71 and 62 through the exhaust passageway 42. The exhaust ports of the engine are thus opened while the crank pins 91 to 94 describe 220° in the construction described. When the crank pin 91 passes through the radial line A—C the port 61 again begins to open the passageway 52 and the gases begin to pass in through the ports 71. The gas continues to pass in to the cylinder 31 as before notwithstanding the fact that the piston 21 has begun to return in the sleeve 31 owing to the vacuous condition produced in the sleeve by the outward movement of the piston. The same cycle of operations is performed by the other engine elements which are thus inter-related in pairs, the sequential operations of the engine elements 1, 3, 4, 2 being in the order enumerated and 90° apart. The same angular relation existing between the ports of each sleeve in their opening and closing throughout the engine elements, there is also a uniform corresponding angular relation of the ports of the sleeves of the engines of the associated pairs so that all of the engine elements will perform the same operation as described in connection with the engine elements 1 and 2.

In Fig. 8 is shown the position of the valves when the piston 21 has performed a half turn showing definitely the location of the sleeve 32 which shows the intake passageway wide open, the pin 101 having moved 90°. The port 61 will be closed when the crank pin 91 passes through the radial line B, although the intake passageway will not be closed until the crank pin 102 has traversed another 90°. In Fig. 9 is shown the next step in the operation of the engine, namely, 102 has passed to the closing line and the crank pin 91 has passed to the radial line A—C while the port 71 is still closed and the exhaust passageway 42 is about to open. The explosion takes place in the cylinder 31 and the piston 21 is driven down and while being carried down the exhaust passageway 42 is being opened to near its widest area. When the crank pin 91 passes through the radial line D, the port 61 begins to open and widely opens while the crank pin 91 is passing under the center of the shaft, namely, from the radial line D to the radial line B, as shown in Fig. 6, allowing practically the whole of the exhausting products to escape. The communication through the pipe 81 remains established until the crank pin 91 passes through the radial line A—C, namely, the top center. Whereupon, the intake passageway begins to open as shown in Fig. 7. The passageways 41 to 44 and 51 to 54 are connected to the manifolds 65 and 67. The exhaust manifold 65 is secured to the casing 12 by means of the bolts 66 while the manifold 67 for the explosive mixtures are secured to the casing 12 by means of the bolts 68. The manifolds cross each other between the communicating passageways which lead to the two adjoining central engine elements and the passageways which lead to the end engine elements. The manifolds 65 and 67 could be located in parallel relation but to produce a uniform height of the engine elements and permit the same degree of relationship between the ports of each sleeve, the manifolds are preferably crossed in the manner shown in Fig. 5. By this arrangement the structure of the engine is greatly simplified which greatly reduces the cost of construction.

The degrees at which the ports may be opened and consequently degrees at which communication through the passageways are established relative to the movements of the crank pins of the engine may be greatly varied whereby the periods during which the ports remain open and the passageways are established may be greatly altered, either increased or diminished, as may be desired. By this means, the periods of intake and the periods of exhaust and the periods of the compression or driving action may be relatively changed and varied as may be desired. The independence of relative location of the ports of the engine cylinders gives opportunity for variation of the timing of the engine with reference to the cycle of operations of the engine. By this means the engine may be so made as to meet the various conditions requisite in the commercial world. If it is desired to produce a heavy power engine, such as, one of a stationary type, it may be readily altered into a six-cycle engine whereby the intermediate step of cleaning the cylinders by passing air or other gas for

- cooling or other purposes may be performed, such as, intermediate the exhaust of the products of combustion and the intake of the explosive mixtures. Also, if it is desired to produce a high speed engine the ports may be readily varied in their location and in their sizes so as to expel the exhaust gases in advance of a low speed engine. It will thus be seen that by merely changing the relative location and the areas of the ports in the cylinders, different types of engines may be produced and different results may be obtained according to which will be the most beneficial under the conditions to which the engine is to be subjected.
- Having thus described my invention, what I claim as new and desire to secure by Letters Patent, is,—
1. The combination of a piston, a cylinder and a shell, the cylinder movable in a one-to-two relation with respect to the piston, the shell having a head extending into the cylinder, the head having passageways for the fuel and exhaust gases, the engine having a passageway communicating with the interior of the shell at the explosion chamber and with the first named passageways, the cylinder having ports for alternately opening and closing the first-named passageways and a port for opening and closing the second-named passageway.
  2. The combination of a casing, a plurality of cylinders, and a plurality of pistons located in the cylinders, each cylinder having a port for controlling the passageways of the fuel and exhaust gases of said cylinder and sub-ports for controlling the passageways controlled by the first-named ports of the other cylinders.
  3. The combination of a casing, a plurality of cylinders and a plurality of pistons located in the cylinders, each cylinder having a port for controlling the flow of the exhaust and fuel gases to another of the cylinders and each cylinder having a port for controlling the gases entering from the passageways controlled by another of the cylinders.
  4. In an engine, the combination of a plurality of pairs of movable cylinders, pistons located in the cylinders, the engine having passageways for exhaust and fuel gases, each cylinder having a port for alternately opening and closing the passageways leading to the other cylinder with which it is associated and a port for controlling the flow of gases into and out of the last named cylinder.
  5. The combination of a casing, a pair of movable cylinders, pistons located in the movable cylinders, heads extending into the cylinders, the heads having passageways for the fuel and exhaust gases, the cylinders having ports for controlling the said passageways and ports for controlling the flow of the gases into and out of the cylinders.
  6. The combination of a pair of movable cylinders, pistons located in the cylinders, heads located in the cylinders, each head having passageways, one for the fuel gas and the other for the exhaust gas of the cylinder, 70 other than the one in which the head is located, the cylinder in which the head is located having a port for alternately opening and closing the passageway.
  7. The combination of a pair of movable cylinders, pistons located in the cylinders, heads located in the cylinders, each head having passageways, one for the fuel gas and the other for the exhaust gas of the cylinder other than the one in which the head is located, the cylinder in which the head is located having a port for alternately opening and closing the passageway, and a port for controlling the flow of the fluid into and out of the cylinder.
  8. The combination of a pair of movable cylinders, pistons located in the cylinders, heads located in the cylinders, each head having passageways, one for the fuel gas and the other for the exhaust gas of the cylinder other than the one in which the head is located, the cylinder in which the head is located having a port for alternately opening and closing the passageway, and a port for controlling the flow of the fluid into and out of the cylinder, the head provided with passageways for a cooling medium.
  9. In an engine, the combination of a source of fuel supply for the said engine, a movable cylinder and a piston, the engine 100 head extending into the cylinder and having a passageway communicating with the source of fuel supply, the cylinder having ports, one located in operative relation with the passageway in the head and the other 105 located below the head for controlling the exhaust and the intake of the cylinder.
  10. In an engine, the combination of a source of fuel supply, a means for conducting away the exhaust products of the engine, a movable cylinder and a piston, the engine head extending into the cylinder and having two passageways, one communicating with the source of fuel supply and the other communicating with the means for 115 conveying away the exhaust products of combustion, the cylinder having a port for controlling the said passageways, and another port for permitting the fuel to enter the cylinder and exhaust products to be 120 drawn from the cylinder.
  11. In an engine, the combination of a pair of elements having valve members and pistons, each valve member having a means for controlling the intake and exhaust gases 125 of the other element, and means coacting with the first named means for controlling its own intake and exhaust gases which are controlled by the other valve member.
  12. In an engine, the combination of a 130

- 6 pair of movable cylinders, pistons located in the cylinders, the engine having two passageways, one for the fuel gas and the other for the exhaust gas of the cylinders, and two passageways connecting the first two passageways to the combustion chambers of the engine, the cylinders having ports, one port of each cylinder for alternately establishing communication between the first two passageways and one of the last named passageways, and each cylinder having a port for establishing communication between the one of the last named passageways and the combustion chamber of the engine.
13. In an engine, the combination of a pair of movable cylinders, pistons located in the cylinders, the engine having two passageways, one for the fuel gas and the other for the exhaust gas of the cylinders of the engine, and two passageways connecting the first two passageways to the combustion chambers of the cylinders, the cylinders having ports, one port of each cylinder for establishing communication between one of the last named passageways and its combustion chamber, and each cylinder having a port for alternately establishing communication between the first two passageways and the passageway of the last named passageways which communicates with the combustion chamber of the other cylinder.
14. In an engine, the combination of a pair of movable cylinders, pistons located in the cylinders, the engine having two passageways, one for the fuel gas and the other for the exhaust gas of the cylinders of the engine, and two passageways connecting the first two passageways to the combustion chambers of the cylinders, the cylinders having ports, one port of each cylinder for establishing communication between one of the last named passageways and its combustion chamber, and each cylinder having a port for alternately establishing communication between the first two passageways and the passageway of the last named passageways which communicates with the combustion chamber of the other cylinder, while the communication is established between one of the two last named passageways and the other cylinder of the engine.
15. The combination of a piston, a movable cylinder and a shell, the shell having a head extending into the cylinder, the head having passageways for the fuel and exhaust gases, the engine having a passageway communicating with the interior of the shell at the explosion chamber, the cylinder having ports for alternately opening and closing the first-named passageways and a port for opening and closing the second-named passageway.
16. The combination of a casing, a plurality of movable cylinders located in the casing, a plurality of pistons movable in the cylinders, the casing having a plurality of passageways for the fuel gases, and a plurality of passageways for the exhaust gases, each cylinder having a port for controlling the said passageways, each cylinder also having a port for controlling the gases entering and leaving the cylinder, a passageway for connecting the interior of the cylinder to the first named passageways.
17. In an engine the combination of a pair of elements, each element comprising a piston, and an inclosing shell, each element having two passageways one for the intake and the other for the exhaust gases, and a third passageway communicating with the first named passageways, and the explosion chamber of the other element, two movable bodies each movable body for opening and closing the third passageway and the other movable body for opening and closing the communication between the first two named passageways alternately with the third named passageway.
18. In an engine the combination of a pair of engine elements, each comprising a shell and a movable piston, each element having two passageways, one for the intake and the other for the exhaust gases, the engine having a pair of passageways each for connecting the first two named passageways of one element to the explosion chamber of the other element, each element having a movable body, one movable body for opening and closing the connection between one of the second named passageways and the first two named passageways of the element with which the movable body is associated and for opening and closing the connection of the other of the second named passageways with the interior of the shell with which the movable body is associated.
19. In an engine having a pair of elements each comprising a movable valve member, a piston and a shell, each shell having two passageways one for exhaust and the other for intake gases of each engine element, two passageways, each of the last named passageways connecting the first two named passageways with the explosion chamber of the shell of the other engine element, each valve member for opening and closing the ends of the second named pair of passageways.
20. In an engine having a pair of elements each comprising a movable valve member, a piston and a shell, each shell having two passageways one for exhaust and the other for intake gases of each engine element, two passageways, each of the last named passageways connecting the first two named passageways with the explosion chamber of the shell of the other engine element, each valve member for opening and closing the ends of the second named pair of passageways, each valve member for opening

- the exhaust passageway of its associated engine element while the other valve member opens the explosion chamber of the engine element with which it is associated and for opening the intake passageway of the engine element with which it is associated while the other valve member closes the explosion chamber of the engine element with which it is associated.
- 10 21. In an engine having a pair of elements each comprising a movable valve member, a piston and a shell, each shell having two passageways one for exhaust and the other for intake gases of each engine element, two passageways, each of the last named passageways connecting the first two named passageways with the explosion chamber of the shell of the other engine element, each valve member for opening and closing the ends of the second named pair of passageways, a packing ring located intermediate the first named passageways and the explosion chamber of each engine element.
22. The combination of a casing, having a pair of engine elements, each engine element having a piston and a valve member, the casing having a plurality of ports controlled by the valve members, each valve member for controlling the exhaust and the intake port of the engine element other than the one with which it is associated and each valve member controlling a port communicating with the exhaust and intake ports and with the explosion chamber of the engine element with which the valve member is associated.
23. The combination of a casing, having a pair of engine elements, each engine element having a piston and a valve member, the casing having a plurality of ports controlled by the valve members, each valve member for controlling the exhaust and the intake port of the engine element other than the one with which it is associated and each valve member controlling a port communicating with the exhaust and intake ports and with the explosion chamber of the engine element with which the valve member is associated.
24. In an engine the combination of a pair of pistons, a valve member associated with each piston, each valve member having a means for controlling the intake and exhaust gases, and means coating with the first named means for controlling the intake and exhaust gases for each piston which are controlled by the member associated with the other piston.
- In testimony whereof, I have hereunto signed my name to this specification in the presence of two subscribing witnesses.

EARL V. SALA.
